UNITED STATES PATENT OFFICE.

EDWARD F. GEHRKENS, OF PITTSFIELD, MASSACHUSETTS, ASSIGNOR TO GENERAL ELECTRIC COMPANY, A CORPORATION OF NEW YORK.

ALTERNATING-CURRENT REGULATOR.

1,014,821.

Specification of Letters Patent. Patented Jan. 16, 1912.

Application filed March 2, 1910. Serial No. 546,947.

To all whom it may concern:

Be it known that I, EDWARD F. GEHRKENS, a citizen of the United States, residing at Pittsfield, county of Berkshire, State of Massachusetts, have invented certain new and useful Improvements in Alternating-Current Regulators, of which the following is a specification.

This invention relates to apparatus for controlling the voltage of a transformer, in such manner that a transformer may be operated through a considerable range of voltage with a constant output or a constant secondary current. The control is effected by cutting out or in successive sections of the primary winding.

The object of the invention is to effect this operation smoothly and gradually, without any sudden change in voltage when a section is cut out or inserted in circuit.

In accordance with the provisions of the patent statutes, I shall hereinafter explain the best mode in which I have contemplated applying the principle of my invention in an actual embodiment thereof. The particular embodiment which I shall describe and illustrate but to which I do not limit myself comprises in general the following instrumentalities, the novel features of my invention being pointed out with particularity in the claims annexed to and made a part of this specification.

a. A transformer with taps in the primary and a secondary which may be arranged for a series parallel connection, as, I have illustrated, or, may be a simple secondary winding.

b. A switch for connecting the secondary winding in series or in parallel. While I have illustrated this switch, it will obviously not be necessary for a simple secondary winding.

c. Two dial switches for changing the tap connections of the primary winding.

d. A switch or switches for disconnecting groups of sections after they have been cut out by the aforesaid dial switches.

e. A compensator whose winding is subdivided into a number of equal sections; the terminals of said compensator being respectively connected permanently to the moving

arms or switch blades of the two dial switches.

f. A set of parallel contact bars respectively connected to taps led out from the subdivisions of the compensator.

g. A set of parallel collector bars arranged at right angles to the contact bars, and having individual resistances connected to them and to a common conductor leading to one side of the power circuit; the other side of said circuit being connected to one end of the primary winding of the transformer.

h. A movable switch member consisting of a plurality of contact fingers insulated from each other and mounted on a common carrier, said fingers being long enough to bear at one end always on their respective collector bars, and at their other ends on one or another of the contact bars according to the position to which they may be moved by the carrier.

i. A two-part commutator controlling a contactor switch in series with the compensator winding, and by means of which the circuit of said winding can be opened.

j. A potential transformer may also be connected with the power circuit supplying current to a rheostat and a voltmeter; said rheostat being operated synchronously with the dial switches, as I have shown. This, however, is not necessary to my invention.

k. An operating motor, shafts and gearing for actuating the dial switches, the disconnecting switch or switches, the rheostat, the commutator, and the compensator switch.

l. A reversing switch and a limit switch for said motor.

The mode of operation of these devices to accomplish the object above set forth will be better understood from the following detailed description, reference being had to the accompanying drawing which shows diagrammatically the circuits and apparatus.

One main 1 of the power circuit is connected to one end of the primary winding 2 of the transformer. This winding is divided into sections, thirteen being shown in the drawing, though this number is immaterial. The secondary winding 3 is also divided into sections, preferably two in number; which by means of a switch 4 can be

thrown into series or parallel connection with the mains 5 leading to the work circuit. In the drawing they are shown connected in parallel.

5 Taps are led out from the sections of the primary winding to clips on two dial switches 6, 7, successive taps being connected to the two switches alternately. The taps are lettered *a*, *b*, *c*, etc., and their corresponding clips are lettered *a'*, *b'*, *c'*, etc., so that the connections can be easily traced. The two sets of clips are arranged concentric with a shaft 8 on which are mounted two switch arms or blades 9, 10, the former 15 angularly in advance of the latter and each co-operating with its respective set of clips. The head of each blade is long enough and the spacing of the clips is such that each blade remains in contact with each clip during the time necessary for the compensator switch to travel over all of the contact bars 20 in both directions.

The shaft 8 is driven by a motor 11 controlled by a reversing switch 11^a or a limit switch 11^b. The motor is connected with the shaft by intermittent gearing; such for example as the wheel 12 containing notches separated by wide teeth with concave ends to fit the periphery of the pinion 13 between 25 its two opposite teeth, whereby the wheel 12 will be moved forward one tooth for each half revolution of the pinion, and will be locked against rotation during the time elapsing between two actuations. The pinion 13 is carried on a counter shaft 14 which is also provided with a worm gear 15 driven by a worm 16 on a short counter shaft having a spur gear 17 meshing with a pinion 18 on the motor shaft. This train of gearing 30 is merely illustrative and may be varied to meet the wishes of the constructor; the essential point being that the counter shaft 14 shall make one-half revolution between 40 two actuations of the shaft 8.

45 At each actuation of the shaft 8 one of the sections of the primary winding of the transformer is cut out or in, depending upon the direction in which the motor is revolving. The switch blades 9, 10 are so set that 50 when one is just about to move from one clip to the next, the other has just engaged a clip, and during the movement of the first blade to another clip, the second blade slides along its clip in constant contact therewith. 55 It thus appears that the sections of the primary winding are never entirely open circuited by the dial switches during their movement. In order, however, to prevent the terminals of the winding from being 60 subjected to excessive voltages, provision is made for disconnecting a certain number of sections after they have been cut out by the dial switches. In the drawing, the first four sections and the second four can thus 65 be disconnected in succession, by means of

the rotary switches 19, 20, each comprising a contact segment 21 adapted to connect the two fingers 22 in circuit with the ends of the adjacent sections of the primary winding. The length of each segment is such that it will cease to bridge these fingers after the four sections which it controls have been cut out by the switch blades 9, 10. These blades are connected by conductors 23 with the terminals of a compensator 24, whose winding is divided into sections from which taps are led to contact bars 25 arranged parallel with and insulated from each other. In the drawing I have shown seven bars, but in practice this number is increased to double that number or even more, in order to secure as fine a subdivision of the changes of voltage as possible. In proximity to the contact bars, but at right angles thereto, are several insulated collector strips 26. In practice, 70 these strips take the form of rings mounted on a drum, on which are also carried the contact bars 25. Connected with each collector strip is a resistance coil 27, the resistivity of said coils being graded, as shown. 75 The other terminals of said coils are all connected to the other main 28 of the power circuit. 80

Movable back and forth over the contact bars is a carrier 29 to which are secured the several double-ended fingers 30, one end of each finger being in constant sliding contact with its respective collector strip 26 while its other end can be drawn over the several contact bars 25 in succession. These ends of the fingers are stepped in their arrangement, as shown, so that they do not part from a contact bar all at the same instant, but one after the other, the leading finger making contact with the next bar before the trailing finger has left the former bar. As the carrier draws the fingers over the compensator contact bars, the sections of the compensator are cut out one after the other, until finally all the fingers rest on the end bar. In order 90 to accommodate all the fingers, the end bars are made wider than the intermediate ones, 95 as shown. 100

Any suitable gearing may be adopted for moving the carrier in synchronism with the dial switches; but I prefer to provide the carrier with a rack 31 meshing with a sector gear 32 which can be oscillated by a connecting rod 33 pivoted to a crank 34 on the end 105 of the counter shaft 14. The crank is so set that it passes its dead centers at the times when the pinion 13 is actuating the wheel 12, and the fingers are resting upon the end bars of the compensator. 110

In series with the coils of the compensator 115 is an electromagnetic switch 35, preferably of the contactor type, whose coil 36 is connected to a supply circuit 37 through a circuit breaker or commutator 38 operated by the counter shaft 14 in synchronism with the intermit- 120

tent gearing. When this contactor is de-energized, it opens the compensator winding, thereby breaking the circuit from the primary winding of the transformer through the compensator. This takes place as soon as all the fingers of the compensator switch are on either of the wide end bars, and before the blade of either dial switch has opened the circuit. With this arrangement, no current is broken by either of the dial switches, but only by the contactor, whose contacts can be readily renewed if they burn out. The burning of the contacts of the compensator switch can be reduced to a minimum by having a large number of taps on the compensator, thereby reducing the voltage between the taps to a very small amount, and also by having a large number of fingers, so that there will be practically no breaking of current but rather a gradual shifting due to the gradually varied resistances between the compensator taps, said resistances having a sufficient capacity to permit the compensator to be left in any position.

When the high tension power circuit is connected across the entire primary winding of the transformer, the minimum voltage will be delivered by the secondary winding. This is obtained when the blade 9 is on the clip a' and the fingers of the compensator switch rest on the left hand end bar 25, as shown in the drawing. It will be noticed that the blade 10 is also in contact with the clip b' , but practically no current will flow through the switch 7, owing to the interposition of the compensator coils. The continued rotation of the motor causes the carrier to traverse the contact bars 25, gradually cutting out the compensator coils, until the fingers rest on the right hand end bar, and the line is then in effect connected directly to the clip b' and the first section of the primary winding is cut out. At this point, the intermittent gearing operates, moving the blade 9 to the clip c' , the blade 10 still remaining on the clip b' . This reverses the polarity of the compensator, so that the reverse movement of the carrier which is now effected by the next half revolution of the crank proceeds to cut out the coils of the compensator from between the clips b' and c' ; thus again gradually increasing the voltage of the secondary of the transformer. This alternating movement of the blades 9, 10 and the intermittent movement of the compensator switch are continued until the entire range of voltage has been covered, or until such a voltage has been reached as is desired. By this arrangement a continuous movement of the actuating shaft produces a uniform range of voltage, and in passing from one tap to another of the primary winding an independent adjustment of the compensator taps is not required; but this

adjustment is automatic and dependent upon the shaft actuating the dial switch blade.

It will be obvious that while I have illustrated the actuating shaft as driven by a motor that this shaft if desired may be operated by hand, or by other suitable means.

With the secondary coils in multiple, the range in the secondary voltage of the transformer, for a complete range of operation of the dial switches, is from 40 to 100 volts, assuming that the apparatus is capable of a range of from 40 to 200 volts in all. To obtain a higher voltage than 100 it is necessary to open the circuit of the entire switching apparatus, so as to disconnect it from the power circuit, and then connect the sections of the secondary winding in series by means of the switch 4. This arrangement

will produce a higher voltage across the secondary winding than was previously obtained, and in order to prevent too sudden a change, the primary switching apparatus must be run back enough to secure the same voltage as before the change was made in the connections of the secondary. This arrangement of the dial switches must be made before they are again connected to the power circuit, and in order to enable the operator to determine the proper adjustment a voltage indicator is provided, which will show at all times what the voltage of the secondary circuit is, whether the transformer is in service or not. The preferred form of indicator is a voltmeter 39 connected to the secondary 40 of a small potential transformer whose primary 41 is across the power mains. This transformer has a double winding, each of 100 volts, arranged as shown in the drawing, and by means of a switch 42, preferably mechanically connected with the series-parallel switch 4 for the secondary of the main transformer, either the full voltage or the half voltage of the potential transformer can be thrown upon the voltmeter; the former when the secondary is connected in series and the latter when it is connected in parallel. The current from the potential transformer passes through a rheostat 43, whose switch arm 44 is mechanically operated by the shaft 8, as by means of sprockets and an endless belt 45. The resistance is such that as the arm moves over the buttons of the rheostat the voltmeter will show approximately the voltage of the secondary winding of the main transformer.

In actual practice, this invention has given entire satisfaction with a transformer capable of delivering 1600 kilo-watts, the line voltage being 2200, and the secondary voltage varying between 40 and 200; the amperes varying correspondingly from 40000 to 8000. The voltmeter shows a perfectly smooth regulation, the efficiency and

power factor of the installation are improved, and the apparatus is found to be especially adapted for use with single phase low voltage transformers having large current capacity.

5 While I have described the disconnecting of a certain number of sections of the transformer winding from the remainder to prevent danger to the winding from excessive 10 voltages, I do not claim this invention which is claimed in a copending application of Walter S. Moody, Serial Number 546,946, filed March 2, 1910.

15 A preferred embodiment of my invention has been described in the above specification. I do not limit myself to this embodiment, however, but seek in the appended claims to cover all embodiments which will be obvious to those skilled in the art, and within the 20 scope of my invention.

What I claim as new and desire to secure by Letters Patent of the United States, is:

1. The combination with a transformer having its primary winding divided into 25 sections and connected at one end with one of the supply mains, of two switches controlling alternate sections of said winding, a compensator having its terminals connected respectively to the moving members of said 30 switches, means for actuating said members, a connection to the other supply main, and means dependent upon said actuating means for shifting said connection from end to end of said compensator.

35 2. The combination with a transformer having its primary winding divided into sections, of two switches each having stationary contacts connected to alternate sections, a movable member for each switch, 40 means for actuating said members, a subdivided compensator having its terminals connected respectively to said members, contacts connected with the divisions of said compensator; a movable switch coöperating 45 with said contacts, and means operating said switch dependent upon said actuating means.

3. The combination with a transformer having its primary winding divided into 50 sections, of two dial switches having their clips connected to alternate sections, a subdivided compensator having its terminals connected to the movable blades of said switches, contact bars connected in between 55 the divisions of the compensator, and a carrier provided with a plurality of stepped fingers adapted to traverse said bars.

4. The combination with a transformer having its primary winding divided into 60 sections, of two dial switches having their clips connected to alternate sections, a subdivided compensator having its terminals connected to the movable blades of said switches, contact bars connected in between 65 the divisions of the compensator, a carrier

provided with a plurality of stepped fingers adapted to traverse said bars, and means for intermittently moving said switch blades when said fingers rest on the end bars.

5. The combination with a transformer having its primary winding divided into sections, of two dial switches having their clips connected to alternate sections, a common shaft for the blades of said switches, a subdivided compensator in circuit with said 70 blades, a switch coöperating with the coils of said compensator, a shaft for actuating said compensator switch, and intermittent gearing between said shaft and the shaft carrying the dial switch blades.

6. The combination with a transformer having its primary winding divided into sections, of two dial switches having their clips connected to alternate sections, a subdivided compensator having its terminals 85 connected to the movable blades of said switches, contact bars connected in between the divisions of the compensator, a carrier provided with a plurality of double ended fingers adapted to traverse said bars, a plurality of collector strips in line with said 90 fingers and making contact with one end thereof, means for moving said fingers over said bars while the blades of the dial switches remain stationary, and connected 95 means for shifting said blades when the fingers are at either end of their travel.

7. The combination with a transformer having its primary winding divided into sections, of two dial switches having their 100 clips connected to alternate sections, a subdivided compensator having its terminals connected to the movable blades of said switches, a common shaft actuating the blades of said switches, contact bars connected in between the divisions of the compensator, a carrier provided with a plurality of double ended fingers adapted to 105 traverse said bars, a plurality of collector strips in line with said fingers and 110 making contact with one end thereof, means for moving said fingers over said bars while the blades of the dial switches remain stationary, and an intermittent gearing connected to the shaft shifting said blades when 115 the fingers are at either end of their travel.

8. The combination with a transformer having its primary winding divided into sections, of dial switches for cutting out sections, a compensator for gradually reducing the voltage of a section about to be cut out, a circuit breaker for opening the circuit through the compensator before a dial switch operates, and means operating in synchronism with the dial switches for actuating said circuit breaker.

9. The combination with a transformer having its primary winding divided into sections, of two dial switches having their clips connected to alternate sections, a sub- 130

divided compensator having its terminals connected to the movable blades of said switches, contact bars connected in between the divisions of the compensator, a plurality 5 of double ended fingers adapted to traverse said bars, a plurality of collector strips each having its own resistance in line with said fingers and making contact with one end thereof, means for moving said fingers 10 over said bars while the blades of the dial switches remain stationary, and means for shifting said blades when the fingers are at

either end of their travel, a circuit breaker opening the circuit through the compensator before a dial switch operates, and means 15 operating in synchronism with the dial switches for actuating said circuit breaker.

In witness whereof, I have hereunto set my hand this 24th day of February, 1910.

EDWARD F. GEHRKENS.
